UNITED STATES PATENT OFFICE.

WILLIAM ARTHUR HOLT, OF OCONTO, WISCONSIN.

LOG-CARRYING CAR.

1,020,824

Specification of Letters Patent. Patented Mar. 19, 1912.

Application filed October 18, 1911. Serial No. 655,291.

To all whom it may concern:

Be it known that I, WILLIAM ARTHUR HOLT, a citizen of the United States, and a resident of Oconto, in the county of Oconto and State of Wisconsin, have invented new and useful Improvements in Log-Carrying Cars, of which the following is a full, clear, and exact description.

The object of the invention is to provide certain new and useful improvements in log-carrying cars whereby the stake pockets and their stakes can be turned in a transverse direction to lay the stakes flat down on the surface of the car body with a view to allow of running the car through a log loader without requiring the removal of the stakes as now practiced.

For the purpose mentioned use is made of a stake pocket pivoted on the car body to allow of turning the pocket to swing the pocket and with it the stake in a transverse direction to lay the stake flat on the car body.

A practical embodiment of the invention is represented in the accompanying drawings forming a part of this specification, in which similar characters of reference indicate corresponding parts in all the views.

Figure 1 is a side elevation of a log-carrying car provided with the improvement; Fig. 2 is an elevation of one end of the same and showing the stakes in place to retain the logs; Fig. 3 is a similar view of the same showing the stakes at one side of the car disengaged from the pockets for unloading the car; Fig. 4 is an enlarged end view of the stake pocket in position on the car; Fig. 5 is a side elevation of the same; Fig. 6 is a transverse section of the same on the line 6—6 of Fig. 5; Fig. 7 is a sectional plan view of the same on the line 7—7 of Fig. 5; Fig. 8 is a sectional side elevation of the same on the line 8—8 of Fig. 7; and Fig. 9 is a perspective view of the retaining device for holding one end of a chain in position on the stake.

The body A of the log-carrying car is mounted on the usual trucks A' and is provided with suitable cross beams A² for supporting the logs B, as plainly indicated in Figs. 1, 2 and 3, the logs being held in place by stakes C arranged on one side of the car body and stakes C' located on the opposite side of the car body, the stakes C engaging at their lower ends pockets D, while the lower ends of the stakes C' engage the

pockets E. The pockets D are pivoted on pivots F held on the cross beams A² to permit of swinging the pockets D in a transverse direction to lay the stakes C flat on top of the car body A adjacent to the corresponding beam A². The pockets E are similarly mounted on pivots F' to permit of swinging the pockets E transversely with a view to lay the stakes C' flat on the car body A adjacent to the car beams A², it being understood that in practice opposite stakes C and C' are arranged on opposite sides of a cross beam A². The car beams A² project at their ends somewhat beyond the sides of the car body A for receiving the corresponding pockets D and E, and the said pockets D and E are open on top and bottom so that when the stakes C and C' are in position in the pockets they extend below the same and abut with their lower ends against the outer faces of the sills A³ of the car body A, as will be readily understood by reference to Figs. 1, 2, 3 and 4. The stakes C and C' are provided with stop pins C² adapted to rest on the upper edge of the corresponding pocket D or E to limit the downward movement of a stake in its pocket.

The back of each pocket D and E is provided with an eye G engaged by a hook G' pivoted on the corresponding side of the cross beam A² so as to hold the pocket D from turning while supporting a stake C or C' in a vertical position. The side of the pocket D or E adjacent to the cross beam A² is provided with a fixed plate H terminating in a hook H' engaging the inner edge of a plate H² secured to the corresponding cross beam A², and the said hook H' together with the hook G' serves to relieve the pivot F or F' of the corresponding pocket of undue strain at the same time holding the pocket normally in a vertical position.

Each of the pockets E is preferably square or rectangular in plan view with the members integrally connected with each other, but the pocket D is preferably U shape in plan view and is provided at its front with a member D' pivotally connected at D² to the forward end of the plate H above referred to, and the free end of the front member D' is provided with a hinged hasp I adapted to engage a keeper I' formed in the outer side member D³ of the pocket D. In order to hold the hasp I in

engagement with the keeper I' use is made of a locking arm J pivoted on the member D³ and adapted to swing over the hasp I and under a retaining arm K secured to the member D³, as will be readily understood by reference to Figs. 4, 5, 7 and 8. The locking arm J is pivotally connected with one end of a link L extending transversely and terminating at its other end in a loop L' adapted to fit onto a block N secured to the top of the car body A to one side of the cross beam A². A turn button N' is mounted on the top of the block N to hold the loop L' normally locked in position on the block N. When it is desired to release a stake C, the turn button N' is given a quarter turn to unlock the loop L' which is now lifted off the block N, and then the operator pushes on the link L with a view to swing the locking arm J outward and downward to release the hasp I, which latter now can readily disengage the keeper I' to permit the member D' to swing into an open position, thus allowing the stake C to drop and release the logs B (see Figs. 1 and 3).

Oppositely disposed stakes C and C' are connected with each other across the top of the uppermost logs B by a chain O, and a second chain P connects the said stakes C and C' with the other a distance below the upper chain O, as plainly indicated in Figs. 1, 2 and 3. The upper chain O is preferably permanently connected with a clevis O' held on the upper end of the stake C, while the chain P is removably connected with the stake C by the use of a locking hook Q engaging one of the links of the chain P after the same has been passed through an opening in the stake, as will be readily understood by reference to Figs. 2 and 9. When it is desired to unload the logs B the hook Q is disengaged from the chain P, and then the front member D' of the pocket D is unlocked to allow the said front member to swing into an open position, as previously explained, thus releasing the stakes C and permitting the logs to be discharged sidewise from the car body A, as indicated to the right in Fig. 1 and in Fig. 3. Hooks Q, similar to the ones mentioned, may be used for fastening the ends of the chains O and P on the stakes C' after the said chains are passed through the openings in the stakes C'.

When the car is emptied and the stakes C and C' are not in use then the pockets D and E can be readily unlocked by disengaging the hooks G' from the eyes G and disengaging the loops L' of the links L from the blocks N. The stakes C and C' can now be swung in a transverse direction onto the top of the car body A owing to the pivotal connection of the stake pockets D and E with the car beams A² by the use of the

pivots F and F'. When the shoes and their stakes are in folded position the car can be readily run through a log loader without first requiring removal of the stakes from the pockets as now practiced.

Having thus described my invention, I claim as new and desire to secure by Letters Patent:

1. A log-carrying car, comprising a car body, provided with sills and transverse beams for the logs to rest on and projecting beyond the sides of the car body, stake pockets pivoted on one side of the projecting end of the said beams, and stakes held in the said pockets and extending below the same to rest against the outer face of the sill. 70

2. A log-carrying car, comprising a car body, provided with sills and transverse beams for the logs to rest on and projecting beyond the sides of the car body, stake pockets pivoted on one side of a projecting end of the said beams and provided with eyes, hooks pivoted on the beams and adapted to engage the said eyes, and stakes held in the said pockets and extending below the same to abut against the outer face of the sill. 85

3. A log-carrying car, comprising a car body, provided with sills and transverse beams for the logs to rest on and projecting beyond the sides of the car body, stake pockets pivoted on one side of a projecting end of the said beams and provided with eyes and retaining hooks, hooks on the said beams engaging the said eyes, retaining plates on the beams and engaged by the said retaining hooks, and stakes held in the said pockets and extending below the same to abut against the outer face of the sill. 95

4. A log-carrying car, comprising a car body provided with sills and transverse beams for the logs to rest on and projecting beyond the sides of the car body, stake pockets pivoted on one side of a projecting end of the said beams, and stakes held in the said pockets and extending below the same to rest against the outer face of the sill, each stake having a stop adapted to rest on the top of the pocket to limit the downward movement of the stake. 105

5. A log-carrying car comprising a car body provided with a transverse beam, projecting beyond the sides of the car body, a stake, and a stake pocket pivoted at one side of a projecting end of the beam to swing transversely to lay the stake flat onto the car body. 115

6. A log-carrying car provided with a stake pocket having its front member hinged to a side member to swing open for releasing the stake carried by the pocket, the other side member having a keeper and the free end of the said hinged front member being provided with a hasp for engagement with the said keeper, a retaining arm secured to the side member having the keeper, 125

a locking arm pivoted to said side member and adapted to swing over the said hasp and under the said retaining arm to lock the said hasp in place in the keeper, and manually-controlled means for actuating the locking arm.

7. A log-carrying car provided with a stake pocket having its front member hinged to a side member to swing open for releasing the stake carried by the pocket, the other side member having a keeper and the free end of the said hinged front member being provided with a hasp for engagement with the said keeper, a retaining arm secured to the side member having the keeper,

a locking arm pivoted on the said side member and adapted to swing over the hasp and under the retaining arm to lock the hasp in place in the keeper, a link connected at one end with the said locking arm, and terminating at its other end in a loop, and retaining means on the car for engagement by the said loop.

In testimony whereof I have signed my name to this specification in the presence of 25 two subscribing witnesses.

WILLIAM ARTHUR HOLT.
